Primary Examiner—Doris V. Coles[57] **CLAIM**

The ornamental design for a mouse trap with ramp and spinning bait bobbin, as shown and described.

DESCRIPTION

FIG. 1 is a front elevational view of the mouse trap with ramp and spinning bait bobbin showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is a cross-sectional view taken vertically at line 7—7 of FIG. 5.

The broken line showing of environment of FIG. 7 is for illustrative purposes only and forms no part of the claimed design.
